UNITED STATES PATENT OFFICE

1,925,909

TELEGRAPH EXCHANGE SYSTEM

Ehrhard Rossberg, Berlin-Siemensstadt, Germany, assignor to Siemens & Halske Aktiengesellschaft, Siemensstadt, near Berlin, Germany, a corporation of Germany

Application April 13, 1932, Serial No. 604,839, and
in Germany April 18, 1931

11 Claims (Cl. 178—2)

My invention relates to a telegraph exchange system, and more particularly to a system of connections for metering and rating connections in telegraph plants, which enables the rate to be paid by the calling subscribers to be determined automatically and in a simple manner, as regards the length and quality (value) of the lines engaged and the duration of engagement.

In telephone service there are known so-called time-zone metering systems, in which companion work switches provided at the home station are adjusted simultaneously with the group or remote selectors reached by setting up the connection. This system has, however, the disadvantage that the metering equipment must at any time be specially adapted to the engagement schedule according to which the connecting lines are connected to the selectors, and that the number of steps of the companion work switches is limited. This drawback becomes particularly noticeable when establishing connections across a plurality of exchanges and when extending an existing telephone system.

The disadvantage mentioned is according to my invention eliminated by transmitting in a connection passing through a plurality of exchanges from each exchange engaged by establishing the connection metering impulses corresponding with the value of the pertaining engaged connecting line, for adjusting or setting the metering or counting mechanisms.

These metering or counting impulses may be sent out either when engaging a selected connecting switching means, prior to the sending out of the next train of selective impulses or also only after finished selection directly following one another from the various exchanges. The value of the individual connecting lines may be indicated either by a certain number of metering or counting impulses or by the length of the metering impulses. The counting equipment at the exchange provided for the counting, preferably the home exchange, has consequently to integrate the metering impulses signaled back according to their number or length respectively. Simultaneously a time switching device may be provided, which also registers the duration of engagement of the line.

Further improvements will appear as the specification proceeds with reference to the drawings affixed thereto.

In the drawings

Fig. 1 is a diagram illustrating the broad principle of my invention,
55 Fig. 2 is a similar diagram, but in greater detail,

Fig. 3 shows part of a complete system based on this principle, in diagram,

Fig. 4, a right hand continuation of Fig. 3, illustrating, for example, a complete telegraph plant for selector or dialing operation, in which 60 the metering impulses for the zone rating are sent back to the home exchange after each selecting step, and Fig. 5 is a diagrammatic view forming a downward continuation of Fig. 3.

Referring to Fig. 1 showing a telegraph system with the exchanges A to G, in which the connecting lines between the exchanges are rated by metering impulses according to the figures marked adjacent to the respective lines. If, for instance, a subscriber of the exchange A wants 70 to communicate with a subscriber of the exchange F, he dials his connection across the exchanges B, D and E, which then has a zone value of $2+3+2+1=8$ zone units.

Fig. 2 shows diagrammatically how the return 75 signaling of the individual zone units takes place. The calling subscriber TS dials across the group selector GW of his exchange V₁ to the exchange V₂ to which leads the toll line FL₁. As soon as on engagement of the exchange V₂ an initiating impulse arrives across the translating relay U₂, the metering impulse sender ZG₂ sends back the zone impulses corresponding with the line FL₁ to the home exchange V₁, where the impulses step round 80 the zone selector ZW. After the further selection across the toll line selector FW of the exchange V₂ the metering impulse sender ZG₃ of the exchange V₃ sends back the metering impulses corresponding with the toll line FL₂ to the exchange V₁, so that the zone selector ZW steps round two 85 further steps. After continuing the selection across the selectors FW and LW of the exchange V₃ a special signal is ultimately sent back to the exchange V₁ on reaching the line TL leading to the desired subscriber TE, so that the time switch ZS commences with the metering of the time and steps round the meter Z of the subscriber TS in 90 accordance with the time and the zone.

An embodiment of my invention is illustrated 100 diagrammatically in Fig. 3 of the drawings. Figs. 4 and 5 are the right-hand side continuation and the downward continuation respectively of Fig. 3. The illustration is confined to the switching elements necessary for establishing or setting up the connection in one direction and for explaining the details of my invention.

When the subscriber TS, the relay termination 105 of whose line-switch is only shown, makes a call, the line-switch VW is marked by reversing the contact er₁ of the receiving relay ER₁, not shown,

which now selects a disengaged group selector GW. When testing, the relays C₁ and T are energized across the line-switch wiper c and the c-wire, whereby the further selection is prepared in 5 known manner.

By the following impulses of the first selective train of impulses the relay A₁ in the group selector is intermittently energized by the contact e₁ across its winding I, so that across the contact 10 42a₁ the circuit for the lifting magnet H prepared by the contact 45c₁ is closed intermittently and the group selector lifted into the desired decade. The simultaneously energized relay P₁ (winding III) remains closed during the train of 15 impulses due to the slow release obtained by the short-circuit winding II. When the train of impulses is finished the relay opens and across the contact 40p₁ closes the circuit for the magnet D which had been prepared during the first lifting 20 25 step, by closing of the contact 39k. The magnet is stepped round in auto-connection with the relay A₁ until when testing for a disengaged relay transmitter U_a the relay P₁ is again energized across the test wiper GW_c. Simultaneously there responds the relay C₂ and across its contacts 60c₂ the relay X₂.

Across the contact 58x₂ the relay ER₂ is reversed into the operating position of rest, so that across the contact 62e₂ and the toll line FL a cut-in 30 impulse is sent to the relay ES₃ in the transmitter unit Ub of the exchange desired (Fig. 4). The relay R₃ being energized will, on reversing the contact 73e₃ into the operating position of rest, send across the contact 79r₃ and the contact 72e₃ of the relay ER₃ a minus impulse back to the differential relay ES₂ at the other end of the line FL so that across the contact 59e₂ in the operating position of rest the relay R₂ is energized and the through connection is effected across the contact 57r₂ (Fig. 4).

In the group selector unit of the home exchange (Fig. 3) the additional equipment for the time-zone meterings has already been switched in, by the direction-responsive slow-acting relay U 45 having been energized across the contacts 8c₁ and 6p₁ and the relay E of the time switch having been switched in by the contact 26u.

The metering impulses are released by the 50 metering impulse sender zg in the transmitter set Ub (Fig. 4), by the magnet DF being energized by the closing of the contact 86c₃ of the relay C₃ connected across the contact 81r₃. The stepping round takes place automatically by means of the interrupter UL₂, the relay G (I) being energized 55 and placing itself in a holding circuit across the contact 84g and the winding II. The selector wiper F₂ thus stops on the last contact, as here the contact 83g is open. Meanwhile the other wiper F₁ of the metering impulse sender Zg has 60 thrice energized the impulse relay J when sweeping across the contacts 2, 3 and 4, since these three contacts are connected to one another and are in successive steps connected to ground by the contact 82d_f controlled by the magnet DF.

The three metering impulses, which should 65 correspond with the value of the connecting line, are sent back to the metering relay ZR of the zone selector (DZW, ZW₁, ZW₂) which is associated with the group selector GW at the home exchange (Fig. 3) in the following way: The relay J (Fig. 4) controls the contact 71i which sends out corresponding positive impulses over the toll line system FL to the receiving relay ES₂ at the other end of FL. The armature 59e₂ of this relay 70 transmits the metering impulses over the b-wire

(containing the wiper GW_b) to the winding of the relay ZR (Fig. 3).

Through the agency of the relay ZH controlled by the contact 15er the circuit for the magnet DZW of the zone selector prepared by the contact 18u is closed in impulses across the contact 19zh, and thereby effects the stepping round of the wipers ZW₁ and ZW₂ by a number of steps corresponding with the arriving metering impulses. The contacts 16zh and dzw serve for insuring the correct stepping, in the customary manner. The contacts of the wiper ZW₁ are connected to the contacts of a time switch ZS, which switch will be described in greater detail hereinafter.

The above described sending back of metering impulses takes place during the establishment of the connection every time a further selective step corresponding with a connecting line is reached. The metering impulses are then received from the zone selector of the home exchange by a stepping round of the zone selector taking place by a number of steps corresponding with the number of metering impulses. As soon as the desired subscriber's connection has been established, however, a characteristic sign is signalled back from a usual answer-back device of this subscriber, such as a double or triple transmission of the erase signal corresponding with the impulse combination "5 times minus", so that in the group selector of the home exchange (Fig. 3) the direction-responsive and strongly retarded releasing relay U is deenergized by counter-magnetization. The relay Z is energized across the contact 12u and by opening of the contact 5z ensures the complete deenergization of the relay U.

The relay Z sends across the contact 3z and the already closed contact 2e a control impulse to the call recording meter GZ in the c-wire of the line-switch or preselector VW, so that this meter is operated for the first time. The relay E is tripped by short-circuiting by means of the contact 25z and remains dead as the holding circuit passing across its own contact 24e is broken. By opening the contact 13e the relay Z is deenergized again. The contact 11z closes during the metering impulses a spare circuit for the short-circuited winding I across the winding III of the relay C₁.

The further metering impulses for controlling the call or conversation meter or counter GZ in the line-switch VW are controlled by the time switch ZS (Fig. 5) which stands under the control of a 20-seconds switch 20''S. Every time this switch reaches the contact 2 the relay M is energized and by the closing of the contact 21m the circuit of the relay N is closed to remain closed across the contact 22n and again to switch in the relay E across the contact 23n, but by opening the contact 14n at the same time the relay N prevents an action of the contact 13e on the relay Z, for the time being. During the next rotation of the 20-seconds switch the circuit prepared for the relay F is closed across the contact 1, which relay energizes the magnet DZS of the time switch across the contact 36f.

In this way the time switch ZS is stepped round by one step during each rotation of the 20-seconds switch, i. e. three steps during one minute.

In Figs. 3 and 5, numerals 101 to 116 have been applied to corresponding wires to enable the circuits to be traced more readily.

The time switch contacts marked 15, 12, 24 and so on, for instance cam-controlled contacts, are closed once after a number of steps corresponding with the figure inscribed, i. e. the contact bearing the figure 15 after 15 steps or 5 minutes, the contact 12 after 4 minutes and so on.

If now the wiper ZW_1 of the zone selector stands on the fifth contact, a ground connection is established in the positions 6, 12 and 18, i. e. after 2, 4 and 6 minutes, the relay Z responding each time 5 and sending out a control impulse for the call recorder GZ . On closure of the contact 24, i. e. after 8 minutes, a metering impulse is sent out again, the relay Z being, however, not directly grounded, but being connected to ground across the contact $38r_1$ and the winding I of the relay X_1 . This relay X_1 has the object to bring about the correct stepping round of the time switch necessary for continuing the time metering into the starting position, through the agency of the wiper 10 ZS_2 of the time switch ZS .

As soon as the clearing sign is given the 20-seconds switch is rendered inoperative when the relays P_1 and C_1 release, due to the opening of the contact $27c_1$, and by the closing of the contact 20 $17c_1$ across the interrupter UI_1 the return of the zone selector is effected by the intermittent operation of the magnet DZW . The time switch ZS is brought into the starting position across the contact $34'c_1$ and the wiper ZS , by the relay F 25 and the magnet DZS controlling each other in interrupter connection.

I claim as my invention:

1. In an automatic telegraph exchange system, a plurality of exchanges, junction lines between 30 said exchanges each consisting of two transmission ways adapted respectively to transmit telegraphic impulses in opposite directions, subscribers' lines in each of said exchanges, automatic switching means at said exchanges for extending a connection from a subscriber's line in one exchange to a subscriber's line in one of the other exchanges by means of dialling impulses sent out 35 by the calling subscriber and transmitted over one of the said two telegraphic transmission ways 40 of each junction line used, and zone metering equipment for determining the charge to be made for the completed connection, said zone metering equipment being controlled by metering impulses sent back over the other of the said two telegraphic transmission ways.

2. In an automatic telegraph exchange system, a plurality of exchanges, junction lines between 50 said exchanges each consisting of a two-wire duplex-operated transmission circuit constituting two transmission ways for transmitting telegraphic impulses in opposite directions respectively, subscribers' lines in each of said exchanges, automatic switching means at said exchanges for extending a connection from a subscriber's line in one exchange to a subscriber's line in one of the other exchanges by means of dialling impulses sent out by the calling subscriber and transmitted over one of the said two telegraphic transmission ways of each junction line used, and zone 55 metering equipment for determining the charge to be made for the completed connection, said zone metering equipment being controlled by metering impulses sent back over the other of the said two telegraphic transmission ways.

60 3. In an automatic telegraph exchange system, a plurality of exchanges, junction lines between said exchanges each consisting of two transmission ways adapted respectively to transmit telegraphic impulses in opposite directions, subscribers' lines in each of said exchanges, automatic switching means at said exchanges for extending a connection from a subscriber's line in one exchange to a subscriber's line in one of the other exchanges by means of dialling impulses sent out 65 by the calling subscriber and transmitted over

one of the said two telegraphic transmission ways of each junction line used, zone metering equipment for determining the charge to be made for the completed connection, and means at the exchanges for sending back over the other of the said two telegraphic transmission ways metering impulses which control said zone metering equipment in accordance with the length or value of the junction lines used. 80

4. In an automatic telegraph exchange system, a plurality of exchanges, junction lines between said exchanges each consisting of two transmission ways adapted respectively to transmit telegraphic impulses in opposite directions, subscribers' lines in each of said exchanges, automatic switching means at said exchanges for extending a connection from a subscriber's line in one exchange to a subscriber's line in one of the other exchanges by means of dialling impulses sent out by the calling subscriber and transmitted over one of the said two telegraphic transmission ways of each junction line used, zone metering equipment for determining the charge to be made for the completed connection, and means at the exchanges for sending back over the other of the said two telegraphic transmission ways metering impulses which control said zone metering equipment in accordance with the length or value of the junction lines used. 90

- made for the completed connection, and means at the exchanges for sending back over the other of the said two telegraphic transmission ways, groups of metering impulses which control said zone metering equipment in accordance with the length or value of the junction lines used, each group of said metering impulses being sent back from one of the exchanges which are selected on extending the desired connection, and corresponding in its number of impulses to the length or value of the junction line engaged. 5
7. In an automatic telegraph exchange system, a plurality of exchanges, junction lines between said exchanges each consisting of two transmission ways adapted respectively to transmit telegraphic impulses in opposite directions, subscribers' lines in each of said exchanges, automatic switching means at said exchanges for extending a connection from a subscriber's line in one exchange to a subscriber's line in one of the other exchanges by means of dialling impulses sent out by the calling subscriber and transmitted over one of the said two telegraphic transmission ways of each junction line used, zone metering equipment for determining the charge to be made for the completed connection, said zone metering equipment being controlled by metering impulses sent back over the other of the said two telegraphic transmission ways, and switching means which after establishing the desired connection initiate the automatic time metering. 10
8. In an automatic telegraph exchange system, a plurality of exchanges, junction lines between said exchanges each consisting of two transmission ways adapted respectively to transmit telegraphic impulses in opposite directions, subscribers' lines in each of said exchanges, automatic switching means at said exchanges for extending a connection from a subscriber's line in one exchange to a subscriber's line in one of the other exchanges by means of dialling impulses sent out by the calling subscriber and transmitted over one of the said two telegraphic transmission ways of each junction line used, zone metering equipment for determining the charge to be made for the completed connection, and means at the exchanges for sending back over the other of the said two telegraphic transmission ways metering impulses which control said zone metering equipment in accordance with the length or value of the junction lines used, each of said metering impulses being sent back from one of the exchanges which are selected on extending the desired connection, and corresponding in its length to the value of the junction line engaged. 15
9. In an automatic telegraph exchange system, a plurality of exchanges, junction lines between said exchanges each consisting of two transmission ways adapted respectively to transmit telegraphic impulses in opposite directions, subscribers' lines in each of said exchanges, automatic switching means at said exchanges for extending a connection from a subscriber's line in one exchange to a subscriber's line in one of the other exchanges by means of dialling impulses sent out by the calling subscriber and transmitted over one of the said two telegraphic transmission ways of each junction line used, zone metering equipment for determining the charge to be made for the completed connection, said zone metering equipment being controlled by metering impulses sent back over the other of the said two telegraphic transmission ways, and switching means which after establishing the desired connection render the zone metering equipment independent of the telegraphic transmission ways. 20
10. In an automatic telegraph exchange system, a plurality of exchanges, junction lines between said exchanges each consisting of two transmission ways adapted respectively to transmit telegraphic impulses in opposite directions, subscribers' lines in each of said exchanges, automatic switching means at said exchanges for extending a connection from a subscriber's line in one exchange to a subscriber's line in one of the other exchanges by means of dialling impulses sent out by the calling subscriber and transmitted over one of the said two telegraphic transmission ways of each junction line used, and zone- and time-metering equipment for determining the charge to be made for the completed connection, said metering equipment consisting of a contact device controlled by metering impulses sent back over the other of the said two telegraphic transmission ways, a further contact device, and a time switch controlling said second device, in order to effect the metering in accordance with the zone of the established connection as well as with the length of time the connection has been used. 25
11. In an automatic telegraph exchange system, a plurality of exchanges, junction lines between said exchanges each consisting of two transmission ways adapted respectively to transmit telegraphic impulses in opposite directions, subscribers' lines in each of said exchanges, automatic switching means at said exchanges for extending a connection from a subscriber's line in one exchange to a subscriber's line in one of the other exchanges by means of dialling impulses sent out by the calling subscriber and transmitted over one of the said two telegraphic transmission ways of each junction line used, zone metering equipment for determining the charge to be made for each completed connection in accordance with the length or value of the junction line used, and a further metering equipment which registers only the number of connections established. 30

EHRHARD ROSSBERG.
